UNITED STATES PATENT OFFICE.

LEVI WILLIAM STOCKWELL, OF CLEVELAND, OHIO, ASSIGNOR TO THE
CLEVELAND ELECTRIC MOTOR COMPANY, OF SAME PLACE.

COMMUTATOR-BRUSH.

SPECIFICATION forming part of Letters Patent No. 337,885, dated March 16, 1886.

Application filed February 26, 1885. Serial No. 157,007. (No model.)

To all whom it may concern:

Be it known that I, LEVI WILLIAM STOCKWELL, of Cleveland, in the county of Cuyahoga and State of Ohio, have invented certain 5 new and useful Improvements in Commutator-Brushes, of which the following is a specification.

My invention relates to electric generators or motors in which wheel-brushes rotate in contact with the commutator-ring.

The object of my invention is to construct the wheel-brush in such manner as to reduce the wear of the parts, and so that it may be adjusted and maintained in proper position 15 relative to the commutator-ring.

The details of my invention are fully set forth below.

In the accompanying drawings, Figure 1 is an inside view of the end plate of a motor, 20 showing my improved commutator-wheel-brushes partly in section and the commutator-ring. Fig. 2 is a horizontal section of the devices shown in Fig. 1. Fig. 3 is a detail view of one of the commutator-wheels and the arm 25 in which it is mounted removed from the socket, and Figs. 4 and 5 are views illustrating a modification in which wheels having V-shaped peripheries run in correspondingly-shaped grooves in the commutator-ring.

30 In the drawings I have illustrated a pair of brushes on each side of the commutator-ring, so that two points of contact on each side of the ring are given. This double contact is used in my motor patented January 8, 1884, No. 291,636. It is obvious, however, that, so far as the primary features of my invention are concerned, it is immaterial whether double contacts on each side of the ring are employed or not.

40 Each pair of brushes is mounted in a casting, A, which is bolted to the end plate, B, of the motor by a thumb-nut, B', suitable insulating-washers being employed, as illustrated, to insulate the casting from the end plate. 45 Each casting is formed with two cylindrical sockets, c, the axes of which preferably lie in radial lines drawn from the center of the commutator-ring. Each commutator-wheel brush D is fast on its journal d, which has its bearings in the bifurcated end e of the brush-spindle

5 die E. A spring-finger, F, is bolted to one side of the bifurcated end e of the brush-spindle and bears upon the projecting end of the journal of the wheel-brush. The effect of this is to cause the face of the wheel on the side 55 opposite to the spring to run in contact with the arm in which it is mounted.

As the brush-wheel, spindle E, and the casting A are formed of brass, a good contact between the wheel-brush and its supports is 60 therefore obtained.

The circuit-wire for each pair of brushes is connected in a post, a, on the casting A, as clearly illustrated in Figs. 1 and 2.

Heretofore, so far as I am aware, where 65 wheel-brushes have been employed, the wheel has been rotated on a stationary axle or pin. The result was, that when the wheel became a little worn there was a sliding motion on the pin, which soon wore out both the pin and the 70 wheel. In my improved construction, however, the wheel is fast on the pin or axle, which rotates in bearings on each side of the wheel. By employing a spring-finger I obtain a good contact between the wheel and the bearing in 75 which its pin or axle turns. This is desirable, because otherwise the lubrication of the bearing of the wheel would tend to increase the resistance of the contacts. The same result may of course be obtained by letting the 80 spring-finger bear on the side of the wheel as close to its axle as possible, so as to hold it in contact with its bearing.

The spindle E of the wheel-brush is formed with a shoulder at f, and carries at its end a 85 collar, g, which slides loosely on the spindle, but is prevented from turning thereon by a cross-pin, h, in the end of the spindle, which lies in slots g' in the sides of the collar. A coil-spring, i, which embraces the spindle, is 90 interposed between the shoulder f of the collar g, so as normally to press the collar away from the shoulder. A spindle thus organized is inserted in its socket c in the casting A, as clearly shown in section in Fig. 1. A set-screw, k, which works in the side of the socket c, binds the collar g. By adjusting the collar in the socket and securing it firmly by the set-screw it is obvious that the pressure of the 95 wheel-brush on the commutator-ring may be 100

adjusted. When the wheel is adjusted properly relatively to the commutator-ring—that is, with the plane of the wheel at right angles to the axis of the commutator-ring—the set-screw will hold the collar, and the pin *h* in the end of the wheel-spindle will prevent the wheel from turning. With this organization, therefore, the pressure of the wheel upon the ring and its proper angular relation to the ring may be maintained. The plungers or spindles which carry the wheels are arranged in radial lines from the center of the commutator. Variations of size in the commutator-rings will not therefore change the points of contact between the commutator-ring and the wheel-brushes. The spindles or plungers of each pair of brushes are shown as set at an angle of forty-five degrees to each other. This, however, may of course be varied, and forms no feature of my present invention.

In order to maintain the brush in proper position relatively to the ring—that is, with the plane of the brush at right angles to the axis of the ring—the ring may be grooved and the brushes formed with correspondingly-shaped peripheries to run in the grooves. This is illustrated in Figs. 4 and 5. In that case, as illustrated in Fig. 5, the slots *g* in the collar and the pin *h* in the end of the brush-spindle may of course be dispensed with.

As indicated at the beginning of this specification, I am of course aware that wheel-brushes are very old, and I do not therefore attempt to claim such broad ground. The use of such brushes possesses many advantages, the principal of which is the reduction of friction.

I claim as my invention—

1. In a commutator for electric motors or dynamos, the combination of the casting in which the socket for the wheel-brush spindle is formed, the wheel-brush and its spindle, the collar and spring on the spindle, and the set-screw.

2. In a commutator for electric motors or 45 dynamos, the combination of the casting in which the socket for the wheel-brush spindle is formed, the wheel-brush and its spindle, the slotted collar and spring on the spindle, and the cross-pin in the spindle. 50

3. In a commutator for electric motors or dynamos, the combination of the casting in which the socket for the wheel-brush spindle is formed, the wheel-brush and its spindle, the slotted collar and spring on the spindle, the cross-pin in the spindle, and the set-screw in the side of the spindle socket which binds the collar in place. 55

4. In a commutator for electric motors or dynamos, the combination of the commutator-ring, the wheel-brush, the axle or pin on which the brush is rigidly mounted, and the bearings for said pin. 60

5. In a commutator for electric motors or dynamos, the combination, substantially as set forth, of the commutator-ring, a wheel-brush which runs thereon, and a spring-finger which holds the wheel in contact with its conducting-support. 65

6. In a commutator for electric motors or 70 dynamos, the combination of the commutator-ring, the wheel-brush which runs thereon, the pin or axle on which the wheel is rigidly secured, the spindle and bearing of the wheel, and the spring-finger which presses on the pin 75 or axle of the wheel, for the purpose described.

7. In a commutator for electric motors or dynamos, the combination, substantially as set forth, of the end plate, the casting *A*, the commutator-ring, the wheel-brushes, their 80 spindles, and the radial sockets for the spindles in the casting.

In testimony whereof I have hereunto subscribed my name.
